UNITED STATES PATENT OFFICE

CHARLES W. KIRSCH AND ARCHIE A. ALLEN, OF STURGIS, MICHIGAN, ASSIGNEES TO
KIRSCH COMPANY, OF STURGIS, MICHIGAN, A CORPORATION OF MICHIGAN

MACHINE FOR EMBOSSED CURTAIN-POLE RINGS

Application filed June 17, 1929. Serial No. 371,432.

This invention relates to improvements in machines for imparting ornamentation to the surfaces of curtain pole rings and particularly to the conventional ring cut from wood. 5 In the instant case, the machine is designed and constructed to effect the surface ornamentation of wood rings by means of a branding roll but we desire it to be understood that for surface ornamentation of rings 10 composed of metal or of material which permits of easy impression without the use of heat, the heating means shown may be omitted.

The main object of the present invention is 15 to provide a very simple and efficient machine for the purpose specified wherein the active elements are moved to exert pressure on the ring to be ornamented by means of compressed air which permits of great variations 20 in the degree of pressure exerted on the ring and also permits of easy control of the operation of the machine.

A further object of the invention is to provide 25 a rotatable carrier for the rings which is moved by air pressure to compress the latter against the ornamenting roll and by a spring to normal position and wherein the said spring and air-pressure means also control and actuate a guide for preventing canting 30 of the rings while undergoing ornamentation.

Other objects of the invention will be pointed out or understood from the following specification.

35 In the accompanying drawings illustrating a suitable embodiment of the machine:

Fig. 1 is a perspective view of a machine constructed in accordance with the invention for imparting surface ornamentation to 40 rings.

Fig. 2 is a front elevation of the same.

Fig. 3 is a plan section of the same on the line 3—3 of Fig. 2.

45 Fig. 4 is a vertical section of the same on the line 4—4 of Fig. 2.

Fig. 5 is a detail vertical section of the same on the line 5—5 of Fig. 3.

50 Fig. 6 is a fragmentary detail sectional view showing the ring carrier and impress-

ing rolls and a ring interposed between said rolls.

The frame of the machine includes the table plate 1 on which two bearing supporting standards 2 and 3 are mounted. The bearings 4 and 5 carried by said standards 2 and 3 receive the end portions of a shaft 6 which is annularly enlarged between said bearings 4 and 5 to provide thrust shoulders for engaging the opposed ends of said bearings. 55

The shaft 6 is equipped with a sprocket wheel 7 at one end over which the sprocket chain 8 is trained for associating the same with a companion sprocket wheel 9 on a shaft 10 which is suitably geared to a source of 60 power such as the electric motor 11 shown. In the instance illustrated, the shaft 10 is journaled in bearings in a gear-box 12 and carries a worm-wheel 13 meshing with a worm on the motor shaft 14. 65

At its other end portion the shaft 6 is equipped with a spur-gear 15 having long teeth, for reasons hereinafter set forth, and outwardly of said pinion, said shaft 6 is equipped with an annularly grooved roll 16. 70 The surface of said groove in the roll 16 is provided, in the instance illustrated, with projecting ornamenting formations which, for example, are adapted to produce impressions in the surface of a ring simulating those of hammered metal. Obviously the surface of said groove of said roll 16 may be formed to produce either depressed or raised 75 ornamentations on the ring surface as desired.

Mounted on opposite sides of the roll 16 80 and suitably supported and held against rotation, are gas-burners 17 having annular rows of gas discharge perforations opposing the side faces of the roll 16 for causing gas jets to impinge upon and maintain said roll hot. These burners 17 are connected by means of a supply pipe 18 with sources of air and gas under pressure and delivering mixed air and gas to said burners 17. This supply 85 pipe 18 is equipped with a valve 19 while the air supply pipe 20 and the gas supply pipe 21 are equipped with valves 22 and 23, respectively. 90

The burners 17 are supported by a bracket 100

24 mounted upon the standard 2 as shown in Figs. 1 and 4.

The standard 2 is provided below the bearing 4 with a vertical slot 25 in which a sleeve-bearing 26 is reciprocable, said bearing being provided with suitable guide flanges to hold it against longitudinal movement in said slot and is mounted upon the upper end of the piston rod 27 of the piston 28 in the cylinder 29 which is mounted upon the lower face of the plate 1, the said piston rod projecting through an opening 30 in said plate.

The cylinder 29 is equipped in its lower face or end with a head 31 having a central bore with which a tube 32 connects, said tube constituting an air supply and discharge chamber and being sealed at its lower end by means of the head or cap 33. Between its ends the said tube or air chamber 32 is connected with an air supply and discharge tube 34. The cylinder 29 is likewise connected at its upper end with an air supply and discharge tube 35. Both these tubes are connected at their other ends with the valve casing 36 which is suitably connected with a source of supply of compressed air and is equipped with exhaust ports. A valve in said casing equipped with the operating lever 37 is arranged so that, when disposed in one position, it seals the air exhaust port for and connects the air supply tube 34 with the source of air under pressure, and when in another position, shuts off the last-mentioned communication, opens the discharge port for and connects the tube 35 with the source of air under pressure.

The piston 28 of the cylinder is moved to and held at the lower limit of its movement by means of the air under pressure supplied through the tube 35, and is forced upwardly by air under pressure supplied to the chamber 32 through the tube 34, details of construction of the valve and casing 36 being omitted from illustration as well-known in the steam and gas-fitting arts.

A spring 38 is attached at its lower end to the frame element 39 and at its other end to a pair of arms 40 which are parallel and pivoted at one end to the block 41 on the table 1 and between their ends bear upon an arm 42 rigidly secured to the vertically reciprocable bearing 26 to normally maintain the latter at the lower limit of its movement. The outer free end portions of the arms 40 are so disposed that the open space between them lies normally below the carrying roll 43 mounted upon one end portion of the shaft 33 journaled in the sleeve-bearing 26. Said roll 43 is provided with an annular groove in which rings 45 to be subjected to the action of the roll 16 are engaged, the carrying roll being of less outer diameter than the openings in the rings 45.

The arms 40 are normally positioned to permit the placing of a ring on the said

carrying roll 43 and, as the said roll is raised under the influence of compressed air admitted to the cylinder 29 below the piston thereof and causing the latter and the bearing 26 to rise, the said arms 40 swing upwardly so that the space between their free end portions receives the lower portion of the ring 45 carried by the roll 43 to prevent said ring from canting out of a vertical plane.

The shaft 44 is equipped with a long tooth spur-pinion which meshes at all times with the companion gear 15 on the shaft 6, said long teeth permitting sufficient separation of the rolls 16 and 43 to mount upon and remove rings from the roll 43. Said rolls rotate continuously in unison and, when a ring 45 is interposed therebetween and compressed air is admitted to the cylinder as above described, said ring 45 will be compressed against the ornamenting surface formations of the groove of the roll 16 and will be rotated to have the ornamentation imparted to its outer surface under the influence of heat and pressure, in the instant case.

In operation, a single operator feeds and removes rings successively with one hand and operates the valve lever with the other hand to introduce compressed air into the cylinder following the mounting of each ring on the roll 43 and to exhaust the air from the cylinder preparatory to removing the ring from said roll.

I claim as my invention:

1. A machine of the kind specified including a carrier roll and an embossing roll geared for rotation in unison in opposite directions, said rolls being separable to permit insertion and removal of an element to be embossed, and manually controlled fluid pressure actuated mechanism associated with one of said rolls for forcing the same toward the other and maintain the said element compressed against said embossing roll.

2. A machine of the kind specified including a carrier roll and an embossing roll geared for rotation in unison in opposite directions, said rolls being separable to permit insertion and removal of an element to be embossed, a spring associated with one of said rolls for normally maintaining said rolls spaced from each other, and manually controlled fluid pressure actuated mechanism associated with one of said rolls for forcing the same toward the other against the action of said spring and maintain the said element compressed against said embossing roll.

3. A machine of the kind specified including a carrier roll and an embossing roll geared for rotation in unison in opposite directions, said rolls being separable to permit insertion and removal of an element to be embossed, and manually controlled fluid pressure actuated mechanism associated with one of said rolls for forcing the same toward the other and maintain the said element compressed

against said embossing roll and means for continuously heating said embossing roll.

4. A machine of the kind specified including a shaft carrying an embossing roll journalled in a bearing rigid with the machine frame, a bearing slidable toward and from said first-named bearing, a shaft equipped with a carrying roll journalled in said slidable bearing, gearing between said shafts for 5 rotating them in unison in opposite directions continuously and permitting relative movement thereof to thereby permit insertion and removal of elements to be embossed; a spring for maintaining said shafts normally spaced 10 apart, and manually controlled fluid pressure actuated mechanisms for forcing said shafts toward each other against the action of said spring and thereby maintain an element on the carrying roll compressed against said 15 embossing roll.

5. A machine of the kind specified including a shaft equipped with an embossing roll, a shaft equipped with a carrying roll for rings to be embossed, manually controlled 25 means including a spring for maintaining the carrying roll normally spaced from the embossing roll and fluid pressure actuated mechanism for forcing said carrying roll toward the embossing roll, against the action 30 of said spring, gearing for continuously rotating said shafts in opposite directions, and a guide member associated with said carrying roll and said manually controlled means, for maintaining a ring in proper position 35 relatively to the embossing roll while pressed against the same.

6. A machine of the kind specified including a pair of parallel shafts, an embossing roll on one thereof, a ring carrying roll on 40 the other thereof, intermeshing spur-gears on said shafts permitting limited separation thereof, a reciprocable bearing for one of said shafts, an arm on said bearing, a spring-held lever having a guide slot to cooperate 45 with the carrying roll engaged with said arm and the machine frame and normally maintaining said reciprocable bearing at the further limit of its movement with respect to the other shaft, and manually controlled 50 means associated with the reciprocable bearing for moving the same against the action of said spring.

7. A machine of the kind specified comprising a pair of rolls arranged to engage 55 and retain a ring between them to rotate the latter, one of said rolls being an embossing roll and the other a carrying roll, gearing for continuously rotating said rolls in unison, a carrier for one of said rolls for moving 60 the same toward and from the other roll, a rocking lever having a guide slot for cooperation with the carrying roll to hold the ring in proper position relatively to the embossing roll during rotation of said ring, a 65 spring associated with said lever and said

carrier for normally spacing said rolls from each other and holding said lever out of position to engage a ring, and manually controlled means associated with said carrier and said lever for moving the same into operative positions against the action of said 70 spring.

8. A machine of the kind specified comprising a pair of rolls arranged to engage and retain a ring between them to rotate 75 the latter about its own axis, said rolls having annular grooves adapted to fit the inner and outer circumferential surfaces of said ring, one of said rolls being an embossing roll and the other a carrying roll, gearing for continuously rotating said rolls in unison, a reciprocable carrier for the carrying roll for moving the same toward and from the embossing roll, a rocking lever having a guide slot for cooperation with the carrying roll to hold the ring in proper position relatively to the embossing roll during rotation of said ring, a spring associated with 80 said lever and said carrier for normally spacing said rolls from each other and holding 85 said lever out of position to engage a ring, and manually controlled means associated with said carrier and said lever for moving the same into operative positions against the action of said spring.

9. A machine of the kind specified comprising a table plate, a pair of standards thereon, bearings for a shaft rigidly mounted in said standards, a shaft equipped with an embossing roll journalled in said bearing, guide means in one of said standards, a bearing reciprocable in said guide toward and from the bearings of said shaft, a shaft equipped with a carrying roll journalled in said reciprocable bearing, an arm on the latter, a rocking lever pivoted at one end to the frame of the machine engaged between its ends with said arm, the other end of said lever provided with a guide slot adapted to receive the free portion of a ring engaged between said rolls, a spring engaged with said lever for normally holding the same out of engaging relation to a ring and holding the reciprocable bearing spaced from the other bearing, gearing for continuously rotating said shafts in unison in opposite directions in all relative positions of said shafts, and a manually controlled compressed air chuck mounted on said table plate and associated with said reciprocable bearing for moving the latter against the action of said spring.

In testimony whereof, we have hereunto set our hands this 5th day of June, 1929.

CHARLES W. KIRSCH. 125
ARCHIE A. ALLEN.
